DESIGN FOR A SHOE

Louis M. Livingston, New York, N. Y.

Application June 9, 1937, Serial No. 69,746

Term of patent 3½ years

To all whom it may concern:

Be it known that I, Louis M. Livingston, a citizen of the United States of America, residing in Manhattan, county of New York, and State of New York, have invented a new, original, and ornamental Design for a Shoe, of which the following is a specification, reference being had to the accompanying drawing, forming part thereof, wherein,

The shaded portions of the shoe represent elastic areas.

I claim:

The ornamental design for a shoe, substantially as shown, and described.

LOUIS M. LIVINGSTON.
